UNITED STATES PATENT OFFICE.

JOHN W. DIETZEL, OF BURGOON, OHIO.

ROOFING COMPOUND.

SPECIFICATION forming part of Letters Patent No. 368,936, dated August 30, 1887.

Application filed May 11, 1887. Serial No. 237,909. (No specimens.)

To all whom it may concern:

Be it known that I, JOHN W. DIETZEL, a citizen of the United States, residing at Burgoon, Sandusky county, Ohio, have invented 5 a new and useful composition of matter—to wit, a Roofing Compound—of which the following is a specification.

My composition consists of the following ingredients, combined in the proportions stated, 10 viz: asphalt, one-half bushel; coal-tar, two bushels; alum, two and one-half pounds; sulphur, three pounds; copperas, two and one-half pounds; Venetian red, three pounds; rosin, three pounds; gum-shellac, one pound; glue, 15 two and one-half pounds; gypsum, three pounds; tallow, three pounds; salt, three pounds; drier, one pound.

The coal-tar should be heated and the gum-shellac first added, as it liquefies slowly. When 20 the shellac is dissolved, the asphalt, which I prefer to heat separately, is added with the other ingredients and the whole thoroughly mingled by agitation. The compound is applied hot.

25 Other ingredients may be substituted for the Venetian red, according to the color it may be desired to give the roof.

I am aware that a compound has heretofore

been used containing the foregoing ingredients except the shellac, glue, and drier, which 30 I add for the increased gloss of the finished work and penetration of the compound and the rapidity with which the composition becomes hard after application; but I am not aware that all of the ingredients of my composition in the proportions stated have been 35 used together.

What I claim as my invention, and desire to secure by Letters Patent of the United States, is—

The herein-described composition of matter 40 to be used as a roofing compound, consisting of asphalt, one-half bushel; coal tar, two bushels; alum, two and one-half pounds; sulphur, three pounds; copperas, two and one-half 45 pounds; Venetian red, three pounds; rosin, three pounds; gum-shellac, one pound; glue, two and one-half pounds; gypsum, three pounds; tallow, three pounds; salt, three pounds, and drier, one pound, substantially 50 as stated.

JOHN W. DIETZEL.
